PLUNGER WITH WIPING FINGERS

Hettye S. Lazarus and Peter L. Lazarus,
New York, N. Y.

Application November 30, 1950, Serial No. 198,340

6 Claims. (Cl. 15—105)

1

This invention relates to a plunger brush. It is an object of the present invention to provide a heavy duty plunger brush adapted for use in water closet bowls, urinals, garbage cans and in other vessels where heavy duty and quick cleaning operations are necessary to effect adequate cleaning of these vessels and wherein by a simple action of flinging of fingers the scrubbing action is easily effected and wherein the brush is provided with a plunger to open up passages within these vessels at the same time the brush is being used for scrubbing action upon the vessel.

It is another object of the present invention to provide a plunger brush construction wherein a plurality of individual scrubbing fingers can be readily provided which will have weighted ends to facilitate the flinging and scrubbing action of these fingers and to impart to the surface being cleaned heavy scrubbing action and wherein cleaning action can be effected under flanges of the various vessels to thereby render such vessels more sanitary by having them cleaned under such flanges.

It is another object of the invention to provide a plunger brush which has a plurality of weighted fingers and wherein two circular rows of these weight fingers are provided by a separation of alternate fingers cut from a common plane and held by a cylindrical rubber band to provide the two rows of fingers concentric with one another.

It is a further object of the present invention to provide an attachment for standard water closet plungers which can be extended downwardly over the handle and upon the conical top face of such plunger and in such a manner as to provide concentric rows of fingers over the plunger body and outwardly thereof.

Other objects of the present invention are to provide a plunger brush of the type above set forth which is of simple construction, inexpensive to manufacture, has a minimum number of parts, compact, easy to manipulate, of long life and efficient in operation.

For other objects and for a better understanding of the invention, reference may be had to the following detailed description taken in connection with the accompanying drawing, in which

Fig. 1 is a top plan view of the plunger brush constructed according to one form of the invention.

Fig. 2 is an elevational view of the brush.

Fig. 3 is an enlarged transverse sectional view of the brush taken on line 3—3 of Fig. 1.

Fig. 4 is a transverse sectional view of a modi-

fied form of the invention where the brush fingers are assembled upon a standard plunger and as an attachment therefor.

Fig. 5 is a fragmentary sectional view of the form of the invention shown in Fig. 4 assembled on a plunger.

Fig. 6 is an illustrative fragmentary perspective view showing the manner in which the rows of fingers are maintained in spaced relationship by the circular rubber ring.

Referring now particularly to Figs. 1, 2 and 3, 10 represents a main body of flexible material having a threaded top opening 11 into which is fitted an operating stick or handle 12 threaded at its end in the usual manner to engage with the threaded opening 11. This body 10 has a plurality of weighted fingers 13 extending laterally therefrom and having respectively weighted enlargements 14 for effecting a heavy scrubbing action. These fingers may extend directly radially outwardly or may be angled with respect to a radial line nearing a tangential position as shown in Fig. 1. The respective fingers are downwardly and outwardly curved and are adapted to slide outwardly or expand under centrifugal action resulting from a twisting or rotation of the operating handle 12. In this manner the fingers are flung outwardly and can reach under the flange of vessels being cleaned so as to do a thorough cleaning job upon such vessels.

In order to provide two concentric rows of fingers and to have one row of fingers extending downwardly to a different elevation from the other row of fingers, alternate fingers are depressed and a circular flexible band 16 is disposed between the rows of fingers. The inner row or depressed fingers are indicated respectively by numeral 13'. These fingers are thus formed of the same shape as the other fingers and have the same weighted end enlargements. Secured to the body 10 and within the inner row of fingers is a plunger cup 17 having the usual heavy outer peripheral flange 18 and by means of a rivet 19 extending downwardly from the bottom of the threaded opening 11 and through the top of the cup 17.

Referring now particularly to Figs. 4, 5 and 6, there is shown a modified form of the invention wherein the fingers are supplied to a standard plunger cup 19 by means of an attachment 21 having two rows of fingers extending outwardly and downwardly as with the preceding form of the invention. The outer fingers are indicated at 13'' and the inner fingers are indicated at 13'''.

55 The attachment 21 has a top hole 22 for receiving

an upstanding attaching portion 23 of the plunger cup 19 and to which operating handle 12 is attached. The rows of fingers lie in the same manner as with the first form of the invention externally of the plunger cup and are separated or expanded when plunger action is effected with the cup. The attachment 21 may utilize the same flexible band or ring 16 for separating the rows of fingers.

In operation, the brush is given a swirling action and the fingers will be extended and will wipe effectively upon the surface being cleaned. Due to the weighted end enlargements, a brisk and heavy rubbing action is effected upon the surface of the vessel being cleaned. To assemble the attachment 21 upon the plunger cap 19 and to retain the same in a rigid position thereupon, the opening 22 is slightly smaller in diameter than the upstanding portion 23 of the cap whereby there is little chance for the attachment 21 to climb upwardly upon the upstanding portion 23. It will be apparent that the brush can be used with but a single row of fingers weighted in the same manner as above described and circumferentially spaced with respect to one another, a slight distance in order to allow for a free swinging movement of the fingers.

It will also be apparent that there has been provided a plunger brush formed of weighted flexible fingers adapted to act upon a surface to be cleaned with a scrubbing action and with heavy force resulting from the weighted ends.

It will be further apparent that the action of these fingers is effected by a twirling, twisting or rotating of the operating handle. The fingers may be provided with a roughened surface to provide more effective scrubbing action.

While various changes may be made in the detail construction, it shall be apparent that such changes will be within the spirit and scope of the present invention as defined by the appended claims.

What is claimed is:

1. A brush comprising a body portion, a plurality of circumferentially arranged downwardly and outwardly curved weighted fingers connected to the body portion, alternate fingers being depressed whereby to provide inner and outer rows of fingers and means extending between the depressed fingers and the fingers which are not depressed to retain the depressed fingers in place to provide the inner row, an operating handle and means securing the body portion to the operating handle whereby upon rotation of the operating handle the weighted fingers will be flung outwardly under centrifugal action to effect a cleaning of the surface of the vessel being cleaned.

2. A brush comprising a body portion having a central threaded opening, an operating handle threadedly connected into the threaded opening, a plurality of outwardly and downwardly curved weighted finger portions circumferentially arranged and connected about the body portion and operable for cleaning action upon a twisting or rotation of the handle, said weighted fingers be-

ing arranged in concentric inner and outer rows, alternate fingers providing an inner circumferential row, means extending between outer and inner fingers for maintaining the inner and outer fingers spaced from one another and in circumferential relationship.

3. A brush comprising a body portion having a central threaded opening, an operating handle threadedly connected into the threaded opening, a plurality of outwardly and downwardly curved weighted finger portions circumferentially arranged and connected about the body portion and operable for cleaning action upon a twisting or rotation of the handle, a plunger cup secured to the body portion and lying under the fingers.

4. A brush attachment adapted for connection to a plunger cup comprising a body portion having an opening therein adapted to be received over the cup, circumferentially arranged outwardly extending weighted fingers adapted to overlie and extend outwardly of the exterior of the plunger cup, said body portion having tight gripping relationship with the plunger cup, alternate fingers being depressed and a flexible band extending over the depressed fingers and under the non-depressed fingers whereby to provide two concentric rows of fingers overlying the plunger cup.

5. A brush comprising a member having a handle attaching portion, an operating handle connected to the handle attaching portion, a suction cup portion secured to the handle attaching portion and a plurality of circumferentially arranged downwardly and outwardly extending finger cleaning portions extending downwardly and outwardly from the attaching handle portion.

6. A brush comprising a member having a resilient body portion and a plurality of flexible circumferentially arranged and curved downwardly and outwardly extending fingers, the body portion and the fingers having the configuration of a plunger, the ends of said fingers being enlarged and weighted, an operating handle connected to said member and to the body portion thereof whereby upon rotation of the operating handle the fingers will be extended by centrifugal action for engagement with a surface to be cleaned.
